UNITED STATES PATENT OFFICE

134,407

DESIGN FOR A BADGE OR THE LIKE

Elmer H. Baumgarten, Shorewood, Wis.

Application August 23, 1941, Serial No. 103,006

Term of patent 14 years

To all whom it may concern:

Be it known that I, Elmer H. Baumgarten, a citizen of the United States and a resident of Shorewood, in the county of Milwaukee and State of Wisconsin, have invented a new, original, and ornamental Design for a Badge or the like, of which the following is a specification, reference being had to the accompanying drawing, forming a part thereof.

In the accompanying drawing:

Fig. 2 is an edge elevation thereof.

While my design is shown embodied in a badge, it is contemplated that the same may be embodied in other similar articles of manufacture without departing from the spirit of the invention.

I claim:

The ornamental design for a badge or the like, substantially as shown and described.

ELMER H. BAUMGARTEN.
